UNITED STATES PATENT OFFICE.

JOSEPH PRESTON CAMPBELL, OF PULASKI, VIRGINIA.

TELEGRAPH-KEY.

No. 826,403.

Specification of Letters Patent.

Patented July 17, 1906.

Application filed January 29, 1906. Serial No. 298,490.

To all whom it may concern:

Be it known that I, JOSEPH PRESTON CAMPBELL, a citizen of the United States of America, and a resident of Pulaski, county of 5 Pulaski, State of Virginia, have invented certain new and useful Improvements in Telegraph-Keys, of which the following is a full and clear specification, reference being had to the accompanying drawings, in which—

10 Figure 1 is a view, partly in section and partly in side elevation, showing my invention applied to a well-known type of telegraph-key; Fig. 2, a plan view thereof, and Fig. 3 a detail section showing the lower contact mounted on the lower lever.

15 The main object of my invention is to provide extremely simple means whereby I obtain, first, a higher speed; second, maximum durability of the contacts; third, highest 20 quality of "writing," and, fourth, lightness of touch, as more fully hereinafter set forth.

Other objects appear in the course of this description.

25 Referring to the drawings by reference characters, A designates the main or key lever, which is pivoted on the trunnions *a*, as usual, is provided with the usual upper contact *b*, and is normally held up by spring *c*. The lower contact *f* is supported in the rear end of 30 a supplemental lever *B*, pivoted at *d* directly under the key-lever, the axis of this pivot being approximately parallel with the axis of the pivots *a* of the key-lever.

The forward shorter arm of the lever *B* is 35 reduced and rounded at *e* and extended loosely through the downwardly-curved forward end of the key-lever, thus forming a pivotal or hinge connection with the key-lever. The lower contact is a considerable 40 distance farther from pivot *d* than the hinge connection to the key-lever. The lower contact is insulatingly supported in a block *g* of insulation and is connected by a flexible insulated wire *h* to the usual spring contact- 45 plate *i* of the switch. The usual connections are made whereby the contacts are made the terminals of the circuit.

Upon depressing the key the contacts will simultaneously move toward each other, and 50 when the key is released sufficiently to permit it to rise both contacts move away from each other.

In operating keys of the type wherein the lower contact is stationary a fair speed can 55 only be maintained by adjusting the contacts so that they will be very close together, and

when so adjusted the trouble known as "sticking" is very apt to manifest itself, especially when working on a heavy current, this trouble being due to the formation of an arc between the contacts during the rapid making and breaking of the circuit. This arc completes the circuit, and therefore renders sending impossible, and in the ordinary key this can only be avoided by making a wide adjustment of the contacts, which is seriously objectionable, because it necessitates a greater movement of the arm of the operator, and therefore results in a material reduction in speed. This trouble is entirely avoided in my invention, as I provide for a very wide separation of the contacts without necessitating either an increased movement of the key-lever or the exertion of an appreciably greater force to depress the key-lever, thereby permitting a maximum speed to be maintained, even on the strongest circuits, with an extremely gentle touch. It will be observed that while in the ordinary keys the movement of the finger end of the key-lever is much greater in all adjustments than the normal distance between the contacts in my device the contrary is the fact, the separation of the contacts being greater than the movement of the lever, as should be the case to secure ideal conditions of operation. Thus augmenting the separation of the contacts within a given time obviously secures another very desirable result. It insures a sharper make and break, and thus improves the quality of the sending by making it more decisive and distinct. Thus mounting both contacts on lever members both of which are movably supported the contacts are, so to speak, suspended in the air, the result of which is that the instrument is rendered practically noiseless and the life of the contacts greatly prolonged.

It will be apparent to those skilled in the art that various mechanical embodiments of the invention are possible, and I therefore do not wish to be limited to the exact arrangement and construction shown.

What I claim, and desire to secure by Letters Patent, is—

1. In a telegraph instrument, a movable key-lever carrying one of the contacts, an auxiliary lever carrying the other contact and connecting means whereby the operation of the key-lever will simultaneously actuate the contacts.
2. In a telegraph instrument, a key-lever

- carrying one of the contacts, a movable member carrying the other contact and connections whereby the operation of the key-lever moves both contacts.
- 5 3. In a telegraph instrument, a key-lever, a pair of movable contacts one of which is carried by the key-lever, and means whereby the contacts are simultaneously brought together or separated by the key-lever.
- 10 4. In a telegraph instrument, an actuating-lever, a pair of contacts both of which are movable, and auxiliary means for simultaneously separating or bringing together the contacts by the movement of the lever.
- 15 5. In a telegraph instrument, a key-lever carrying a contact, and an auxiliary lever pivotally mounted and having its shorter

arm connected to the key-lever and its longer arm provided with a contact, for the purpose set forth.

6. In a telegraph instrument, a key-lever carrying a contact, and an auxiliary lever pivoted under the key-lever and having one arm connected to the key-lever and its other arm provided with a contact, for the purpose set forth.

In testimony whereof I hereunto affix my signature, in the presence of two witnesses, this 27th day of January, 1906.

JOSEPH PRESTON CAMPBELL.
